US00D949780S

(12) **United States Design Patent** (10) **Patent No.:** **US D949,780 S**
Diebel et al. (45) **Date of Patent:** **** Apr. 26, 2022**

(54) **BATTERY FOR AN ELECTRONIC DEVICE**

(71) Applicant: **Apple Inc.**, Cupertino, CA (US)

(72) Inventors: **Markus Diebel**, San Francisco, CA (US); **Melody L. Kuna**, Palo Alto, CA (US); **Carli E. Oster**, San Francisco, CA (US); **Florence Wong Ow**, Burlingame, CA (US); **Mikael Silvanto**, San Francisco, CA (US); **Alex Chun Lap Yeung**, South San Francisco, CA (US)

(73) Assignee: **Apple Inc.**, Cupertino, CA (US)

(**) Term: **15 Years**

(21) Appl. No.: **29/687,166**

(22) Filed: **Apr. 11, 2019**

Related U.S. Application Data

(63) Continuation of application No. 29/662,277, filed on Sep. 4, 2018, now abandoned.

CLAIM

The ornamental design for a battery for an electronic device, as shown and described.

DESCRIPTION

FIG. 1 is a bottom front perspective view of a battery for an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the battery for an electronic device that form no part of the claimed design.

1 Claim, 6 Drawing Sheets
